(57) **CLAIM**

The ornamental design for goggles adapted to receive a device, as shown and described.

DESCRIPTION

FIG. 1 is a front perspective view of the goggles adapted to receive a device in an open position, showing my new design;

FIG. 2 is a front view, thereof;

FIG. 3 is a rear view, thereof;

FIG. 4 is a top plan view of said goggles being in the open position, thereof;

FIG. 5 is a bottom plan view of said goggles being in the open position, thereof;

FIG. 6 is a side view of said goggles, with the opposite side view being a mirror image, thereof.

FIG. 7 is an exemplary diagram showing the use of the goggles adapted to receive a device in an environment, the broken lines being shown for illustrative purposes only and form no part of the claimed design;

FIG. 8 is a front perspective view of said goggles in a closed position, thereof;

FIG. 9 is a top plan view of said goggles being in the closed position, thereof;

FIG. 10 is a bottom plan view of said goggles being in the closed position, thereof; and,

FIG. 11 is a side view of said goggles in a closed position, with the opposite side view being a mirror image, thereof.

In all figures, any showing of the environment and/or drawing disclosure and/or device by broken lines is for illustrative purposes only and forms no part of the claimed design.

(Continued)

The said goggles design comprises a chamber which can expand and contract. Accordingly, the specification and enclosed drawings provide the design in a closed and open position, as set forth below.

1 Claim, 11 Drawing Sheets
